THOMAS WAKEFIELD, OF FILLMORE, NEW YORK, ASSIGNOR TO HERBERT C. CLINE, OF FILLMORE, NEW YORK.

BRIDGE-WALL FOR FURNACES.

1,250,732.

Specification of Letters Patent. Patented Dec. 18, 1917.

Application filed December 21, 1916. Serial No. 138,244.

To all whom it may concern:

Be it known that I, THOMAS WAKEFIELD, a subject of the King of Great Britain, residing at Fillmore, in the county of Allegheny and State of New York, have invented a new and useful Bridge-Wall for Furnaces, of which the following is a specification.

This invention has reference to bridge walls for furnaces, and its object is to provide a bridge wall which may replace brick bridge walls, and at the same time cause smoke from the fire to be consumed.

In accordance with the present invention the bridge wall is a structure distinct from the grate bars or other supports, so that the grate may be replaced or wholly changed in character without effect upon the bridge wall or any part of it. The bridge wall includes a series of bars mounted in inclined position, as is customary, and constructed to provide for the passage of air between them. Associated with and underlying the bridge wall bars, is a damper structure so constructed that a certain minimum amount of air will always pass through the damper from the ash pit to and between the bridge wall bars, while the air flow may be increased from such minimum amount to a maximum amount, at will. Furthermore, the damper is so arranged that ashes falling through the spaces between the bridge wall bars may be directed into the ash pit, whereby accumulations of ashes between the bridge wall bars is avoided.

The structure admits of the use of various grades of coal, dry or wet, and operates effectively whether the fire be clean or dirty, the damper structure permitting accommodation to the various conditions which may arise.

The invention will be best understood from a consideration of the following detailed description, taken in connection with the accompanying drawings forming part of this specification, with the further understanding that while the drawings show a practical form of the invention, the latter is not confined to any strict conformity with the showing of the drawings, but may be changed and modified so long as such

changes and modifications come within the scope of the appended claims.

In the drawings:

Figure 1 is a perspective view of a bridge wall embodying the invention, and showing the rear end of a portion of a grate, some parts of the view being in section.

Fig. 2 is a perspective view of the support for the bridge wall bars.

Fig. 3 is a view of the adjustable damper member which in the installed structure is associated with the support shown in Fig. 2.

Referring to the drawings there is shown a series of grate bars 1 which at their rear ends are carried by a member 2 shown as an angle bar which is assumed to be properly mounted at the ends in the furnace walls, thus permitting the use of any type of grate by the use of an appropriate support 2. The furnace chamber is provided to the rear of the grate with an upright wall 3 having at the top a longitudinal enlargement or bulb structure 4. The wall 3 has secured to it at its lower end a plate 5 extending horizontally lengthwise of the wall and also toward the support 2 which it may meet. The plate 5 and the wall 3 are suitably connected together as by lugs 6 on the wall and rivets or bolts 7 traversing the lugs and a corresponding portion of the plate 5, whereby the wall 3 and plate 5 are connected as an effectively single structure. The plate 5 is pierced by a suitable number of passages 8, and supported from the under face of the plate 5 by hinges 9 or otherwise is a damper 10 which in the particular structure shown is made up of longitudinal bars 11 and cross plates 12, which latter are spaced apart sufficiently to leave openings 13 between them. The spacing of the plates 12 is such that when the damper is closed and substantially horizontal they will underlie the openings 8, but the whole damper is spaced from the plate a short distance below it so that air may always pass from the ash pit of the furnace, indicated at 14, upwardly about the plates 12 through the passages 8. Any suitable manipulating means may be provided for actuating the damper and in the drawings such manipulating means are simply

100

indicated by a manipulating reach rod 14 pivoted to a lug 15 on one of the bars 11 of the damper, the purpose being to hold the damper closed, in which position a minimum amount of air may flow through it, or to open the damper to any desired extent, one degree of opening being indicated in dotted lines in Fig. 1.

The bridge wall includes a series of bars 16 of web and flange construction with side lugs 17 spacing each bar from its neighbor, so as to produce air passages 18 between the bars. At one end each bar 16 is formed with a hook projection 19 arranged to hook over the bulb 4 while the other end 20 of the bar is snaped to rest on the plate 5 near the edge thereof remote from the wall 3, this construction being such that the bridge bars incline at a suitable angle. Adjacent to the hook 19 each bar 16 is formed with a notch 21 permitting air to flow close to the hook end, thus keeping it relatively cool. The bulb 4 has a reduced portion 22 permitting the removal of a single bar 16 at a time so that by first removing the bar or bars, if any, between a broken or damaged bar and the reduced portion 22, such damaged or broken bar may be replaced without the necessity of removing all the bridge bars or without the necessity of scrapping an entire bridge, as would be the case if it were a single casting instead of including a suitable number of small castings represented by the individual bridge bars.

35 When the bridge wall is in operation and the grate bars 1 support burning fuel, a minimum amount of air continuously flows through the damper and through the air ducts in the bridge wall. With certain kinds 40 of fuel and with the fire clean such amount of air may be found sufficient to cause combustion of smoke coming from the burning fuel, so that the bridge wall then acts as an efficient smoke consumer. At the same time such amount of air is sufficient to maintain 45 the bridge wall in a workably cool condition.

The air reaching the bridge wall bars through the damper first passes along the under face of the grate, thus becoming more 50 or less heated with the heat increasing as the heated air passes through the damper and through the hot bridge wall bars, all this contributing to the efficiency of the air in causing the burning up of the smoke.

55 Fuel of certain grades or fuel under certain conditions requires a larger amount of air than the minimum amount continuously flowing through the closed damper. Under such circumstances the smoke is not completely consumed and hence it is necessary to provide a greater amount of air which may be done by opening the damper to the requisite degree. This, of course is readily performed by a suitable manipulation of the

reach rod 14 or other structure which may be 65 provided for the actuation of the damper.

A certain amount of ashes always finds its way between the bridge bars and the ashes are caught upon the plate 5 and the plates 12 underriding the openings 8. The 70 damper 10 is located in underlying relation to the plate 5 and the bridge wall bars, so that such ashes as may fall through the group of bridge wall bars naturally gravitate to the plates 12 and to the portions of 75 the plate 5 between the passages 8. These last-named portions may be relatively narrow, so that only a small amount of ashes can ever accumulate thereon, while the greater portion of the ashes passing between 80 the bridge wall bars reaches the plates 12. If the damper be in the closed position the ashes will accumulate on the plates 12, but may be dumped from time to time by momentarily opening the damper. If the 85 damper be already opened as occurs under some conditions, the plates 12 will then be in a slanting position because of the hinging of the damper along one edge and ashes reaching the plates will naturally slide therefrom into the ash pit.

In this way the space beneath the bridge bars is always kept free from any such accumulations of ashes as might reach the bridge bars and cause them to be burned out, such burning occurring very rapidly in the event of the ashes reaching the bridge bars. The damper therefore not only performs the functions of a damper, but of a grate, keeping the space beneath the bridge 100 wall bars free from accumulations of ashes detrimental to the bridge wall bars.

While the supporting wall 3 for the bridge bars is shown in the form of a plate, it will be understood that it may be of any suitable 105 construction and arranged in any suitable way to constitute a support for the bridge bars and for the plate 5, so that the bridge wall structure including the bridge wall bars may be entirely independent and separate 110 from the support for the grate bars and may be installed in a furnace in connection with any suitable type of grate, replacing brick or other bridge walls which may have been installed in the furnace.

115 What is claimed is:—

1. A bridge wall for furnaces having grate bars, comprising a series of slanting bars rising away from the grate bars, a support for the slanting bars having a substantially horizontal portion underlying the bars and provided with passages therethrough, and an upright portion carrying the high ends of the slanting bars, and a pivoted damper 120 underlying the substantially horizontal portion and provided with a series of passages alternating with those of said horizontal portion, the substantially horizontal 125

portion and the damper having coating means for preventing tight closure of the damper, whereby to provide minimum air passages when the damper is in a substantially horizontal closed position.

2. A bridge wall structure for furnaces having grate bars and a support for the rear ends of the grate bars, comprising bridge bars, a support for the bridge bars, 10 separate from the support for the grate bars and including a substantially upright and a substantially horizontal portion, for sustaining the bridge bars in a slanting position with their lowermost ends adjacent to the grate bars, and a hinged damper underlying the horizontal portion of the support, said damper and horizontal portion of the support each having passages therethrough, with the passages of one alternating with those of the other to form a substantially continuous support for ashes falling through the bridge wall when the damper is closed, the parts of the damper registering with the passages through the horizontal portion of the support being in a lower plane than and spaced from the horizontal portion of the support when the damper is in the closed position.

3. A bridge wall structure for furnaces having grate bars and supporting means therefor, comprising slanting bridge bars, a substantially horizontal plate with spaced passages therethrough, one edge of the plate being located adjacent to the support for the grate bars, a wall rising from that edge of the plate remote from the grate bars and constituting a support for the upper ends of the bridge bars with the lower end resting on the plate adjacent to the support for the grate bars, and a damper in underlying relation and hinged to the plate and provided with spaced passages alternating with those through the plate, the parts of the damper between the passages therethrough being at all times spaced from the plate.

4. A bridge wall structure for furnaces having grate bars and supporting means therefor, comprising slanting bridge bars, a substantially horizontal plate with spaced passages therethrough, one edge of the plate being located adjacent to the support for the grate bars, a wall rising from that edge of the plate remote from the grate bars and constituting a support for the upper ends of the bridge bars with their lower ends resting on the plate adjacent to the support for the grate bars, and a damper in underlying relation and hinged to the plate and provided with spaced passages alternating with those through the plate, said damper having spacing devices thereon for holding those parts of the damper between the spaces therethrough in spaced relation

to the solid parts of the plate toward which the damper closes.

5. A bridge wall structure for furnaces having grate bars and supporting means therefor, comprising bridge bars with air passages through which ashes may fall, a substantially horizontal damper seat with spaced passages and with the front edge adjacent to the rear ends of the grate bars, said damper seat being in underriding relation to the bridge bars, and a hinged damper underlying the damper seat and movable toward and from the latter about its hinges, said damper having spaced passages therethrough alternating with those through the seat and said damper having spaced means for holding the damper in spaced relation to its seat when the damper is closed, whereby the closed damper and seat constitute a substantially horizontal support for ashes falling through the bridge wall, and the spacing of the damper from its seat provides for the constant admission of a minimum amount of air to the bridge wall when the damper is in the closed position.

6. In a furnace having grate bars and a support for the rear ends of the grate bars, a bridge wall comprising a substantially horizontal plate extending rearwardly from the grate bar support, an upright wall rising from the rear edge of said plate, bridge bars each carried at one end by the upper end of the upright wall and slanting downwardly to and supported at the lower end by the front end of the horizontal plate, the assembled bridge bars having air passages through which ashes may fall, and a damper underlying the horizontal plate and comprising longitudinal bars and spaced transverse plates, with the bars on the face of the damper toward the horizontal plate and the spaced plates defining passages between them alternating with the passages through the horizontal plate, whereby the damper when closed toward the horizontal plate to a substantially horizontal position constitutes, together with the horizontal plate, a support for ashes falling through the bridge wall.

7. In a furnace having grate bars and a support for the rear ends of the grate bars, a bridge wall structure comprising a substantially horizontal plate with passages therethrough extending rearwardly from the support for the rear ends of the grate bars, an upright wall rising from the rear edge of the plate, bridge bars carried at their upper ends by and extending from the upper edge of the upright wall and slanting downwardly and forwardly to and resting at their lower ends upon the front edge of the horizontal plate, and a hinged damper underriding the horizontal plate

and movable toward and from the under face thereof and provided with means for spacing the damper from the plate when the damper is in a horizontal position, 5 whereby the damper when in the closed position is so spaced from the plate as to constantly admit a minimum amount of air through the bridge bars.

In testimony, that I claim the foregoing as my own, I have hereto affixed my signature in the presence of two witnesses.

THOMAS WAKEFIELD.

Witnesses:

R. H. COLBURN,
H. C. CLINE.

It is hereby certified that Letters Patent No. 1,250,732, granted December 18, 1917, upon the application of Thomas Wakefield, of Fillmore, New York, for an improvement in "Bridge-Walls for Furnaces," were erroneously issued to Herbert C. Cline, as assignee of the entire right in said invention, whereas said Letters Patent should have been issued to the inventor, *said Wakefield, and Herbert C. Cline*, said Cline being owner of *one-half* only of said invention, as shown by the records of assignments in this office; and that the said Letters Patent should be read with this correction therein that the same may conform to the record of the case in the Patent Office.

Signed and sealed this 14th day of May, A. D., 1918.
